UNITED STATES PATENT OFFICE.

JAMES MUTTON, OF FRISCO, UTAH TERRITORY.

CAR-BRAKE.

SPECIFICATION forming part of Letters Patent No. 392,745, dated November 13, 1888.

Application filed July 16, 1888. Serial No. 230,105. (No model.)

To all whom it may concern:

Be it known that I, JAMES MUTTON, of Frisco, in the county of Beaver and Territory of Utah, have invented a new and Improved 5 Car-Brake, of which the following is a full, clear, and exact description.

My invention relates to an improvement in car-brakes, and has for its object to provide a simple and effective means whereby, in the 10 event of a collision, or when the train is brought to a stand, the brake will be automatically applied to the wheels.

The invention consists in the construction and combination of the several parts, as will 15 be hereinafter fully set forth, and pointed out in the claims.

Reference is to be had to the accompanying drawings, forming a part of this specification, in which similar figures of reference indicate 20 corresponding parts in all the views.

Figure 1 is a partial bottom plan view of a car having my improvement applied. Fig. 2 is a longitudinal section on line $x-x$ of Fig. 1, and Fig. 3 is a partial transverse section on 25 line $y-y$ of Fig. 1.

In carrying out the invention a transverse beam, 10, is attached to the longitudinal floor-timbers 11 of the car, which beam is adapted to project vertically downward at the rear of 30 the draw-bar 12 and in front of the axle 13, near the latter. At the rear of the transverse beam 10, and in front of the axle, short bars 14 are secured to the floor-beams, one at each side of the car, as best shown in Fig. 3.

From the short transverse bars 14 a rectangular strap-yoke, 15, is loosely suspended, extending below the bar and having secured to its under side a brake-shoe, 16, which shoe is adapted to engage the wheels, as best shown in 40 Fig. 2. The brake-shoes 16 are normally held in contact with the wheels through the medium of a spring, 17, preferably elliptical, which spring has a bearing respectively upon the inner face of the under horizontal section 45 of the yoke and against the under surface of the short transverse bars 14, as best shown in Fig. 3.

Between the draw-bar and the transverse beam 10, and parallel with the latter, a revolute shaft, 18, is journaled provided with a central eye, 19, the said eye being connected

with the draw-bar, which draw-bar is adapted to be reciprocated by a chain or rope, 20, and the said shaft-eye is likewise connected by a similar chain or rope, 21, with a vertical rotary brake-shaft, 22, held in bearings to project above the sill and provided with the usual hand-wheel, as best shown in Fig. 2.

One end of a lever, 23, is attached to the upper end of the yoke 15 and fulcrumed upon 60 the transverse beam 10, the other end of said lever being secured by a rope or chain to the rotary shaft 18, as best shown in Figs. 1 and 2.

It is evident that when the cars are coupled and drawn ahead, the draw-bar, when pulled 65 out, will turn the shaft 18, and the latter acting upon the lever will raise the brake-shoes. As soon as the cars stop traveling the draw-bar returns to its normal position and the springs 17 act and apply the brakes. In back- 70 ing the brake is reversed by manipulating the brake-shaft 22.

A wear-plate, 24, is attached to the transverse beam 10, upon which the yoke and brake-shoe slide. The spring encircling the draw-bar may be dispensed with if desired. 75

Having thus described my invention, what I claim as new, and desire to secure by Letters Patent, is—

1. The combination, with a sliding draw-bar 80 and a rotary shaft attached to the same, of a spring-actuated vertically-reciprocating yoke, a brake-shoe attached to said yoke at its bottom, and a lever attached to said shaft and to the top of the yoke, substantially as shown 85 and described, whereby the shoe is held upon the wheels of a car when at rest and disengaged when in motion, as set forth.

2. The combination, with a sliding draw-bar, a rotary shaft attached to the same, the 90 axle, and a transverse beam intervening the axle and shaft, of a spring-actuated vertically-reciprocating yoke, a brake-shoe attached to the under side of the yoke, a lever fulcrumed upon said beam and connected at one end 95 with the upper end of the yoke, and a flexible connection between said lever and the roller of a vertical brake-shaft, substantially as shown and described.

3. The combination, with a sliding draw-bar, a rotary shaft attached to the same, the 100 axle, a transverse beam intervening the axle

and shaft, and a vertical brake-shaft; of a
spring-actuated vertically-reciprocating yoke,
a brake-shoe attached to the under side of the
yoke, a lever fulcrumed upon said beam and
5 united at one end to the upper face of the yoke,
and a flexible connection between the lever
and rotary shaft and between the rotary shaft
and the roller of the brake-shaft, substantially
as shown and described.

JAMES MUTTON.
